UNITED STATES PATENT OFFICE.

ALEXANDER LEVETT, OF NEW YORK, N. Y., ASSIGNOR TO THE ZUCKER & LEVETT CHEMICAL COMPANY, OF SAME PLACE.

BUFFING OR POLISHING WHEEL.

SPECIFICATION forming part of Letters Patent No. 269,688, dated December 26, 1882.

Application filed January 20, 1882. (No model.)

To all whom it may concern:

Be it known that I, ALEXANDER LEVETT, of the city of New York, in the county and State of New York, have invented certain new and useful Improvements in Buffing or Polishing Wheels; and I do hereby declare the following to be a full, clear, and exact description of the invention, such as will enable others skilled in the art to which it appertains to make and use the same, and of its mode or manner of operation, reference being had to the accompanying drawings, making part of this specification.

My invention relates to yielding buffing or polishing wheels, such as are usually made of cloth, leather, and other fibrous yielding material. As such wheels are now generally made, materials of the proper thickness are placed together and stamped or cut out of the size and shape of the wheel required and caught together, or fastened in other ways. A hole is then punched in the center, and the wheel is fastened between the flanges or washers, or in some other manner fastened upon the spindle of the machine. In the manufacture of such wheels it is important to cut the material in such a manner as to incur as little waste as possible, as the cost of the material is the greatest item of the expense of producing the wheels. Another mode of forming polishing-wheels is to form the same of irregular scraps or fragments of yielding material fastened together in suitable manner, and various forms of devices of this kind are now the subject of pending applications.

One of the chief objections to wheels constructed as first above described is that the materials of which they are composed are not on all sides of the same degree of strength, and the wheel cut out of them wears away at some places much more rapidly than at others, the result of which is that the wheel wears unevenly and becomes angular after comparatively little use, and is therefore very unsatisfactory for work.

The object of my invention is to make a buffer which shall be practically of an even degree of strength around the entire circumference, and which can be made cheaper than

wheels formed of pieces of material of the shape 50 of the wheel.

In the drawings I show my invention applied to a large buffing-wheel.

Figure 1 shows a piece of material laid out in patterns to which the same is to be cut, and 55 Fig. 2 shows a wheel made of such patterns.

Similar letters of reference indicate like parts.

I take the material of which the wheel is to be made and cut it into sections or sectors, as shown in Fig. 1. These sectors are of such 60 shape that when a number of them are properly placed they may be formed into what is substantially a complete wheel. In this figure the several parts *a* may be cut again across the middle and made of the size *b*, or they may be 65 folded upon themselves or around the annular part *I*, as shown at *a''*, Fig. 2. The parts *c c* are shown disposed in Fig. 2, so that none of the material is wasted. In this example of the invention I show the sectors attached to a 70 rounded sheet of material, *I*, out of which the sections *g g* have been cut, having a hole in the center, through which the spindle is to pass. Around the annular circumference of the piece *I* the sectors are disposed and fastened. One 75 of such sectors *a* is shown riveted to this ring at *a''*. The pieces *a* are shown folded around the ring and caught at *a'* with a wire fastener. *b b* are shown fastened with rivets, and so, likewise, are the pieces *c c*. A convenient way of attaching the sectors in position 80 would be to take two round pieces of metal of a suitable circumference, lay the sectors between them, and then rivet through the whole mass and provide a hole in the center for the 85 spindle.

If desired, a piece of material may be placed on the outside, on each side of the sectors, such pieces being of the full size of the wheel, which will give a finished appearance, and through 90 this also a seam may be run around the wheel to hold the parts together.

In making the smaller wheels all the support needed to hold the parts together will be supplied by sewing a piece of material on the outside, as stated, or running a row of stitching around the central part, for when the wheel is placed on the spindle and tightened up between 95

the flanges the pieces are held firmly together thereby.

I do not limit myself to fastening the sectors together or around the center in any particular manner, as they may be fastened in a variety of ways, as will suggest themselves to any one familiar with the art.

When the parts have all been attached the wheel may be rounded in any convenient manner, and is used in the same way as the wheels now made, being fastened on the spindle between washers or flanges in the usual way. By this arrangement and construction I am able to make a wheel which will be substantially of equal strength around its entire circumference, for it is apparent that the outer circumferential edge of each piece cuts on the same line of the material, and in the example shown in the drawings is parallel to the sides of the material, and the fibers of all the sectors are disposed to present portions of the material which are of equal strength to the entire operating-surface of the wheel, while if the wheel had been cut from material in the usual manner its circumferential edge would be of unequal strength. This will be readily seen by taking a disk of muslin and holding it so that one set of threads is perpendicular. At the top and bottom of the disk, where the perpendicular threads are the longest, the horizontal threads crossing them are the shortest. The same is true of the horizontal threads. Where they are longest the perpendicular threads crossing them are shortest. Now, these short threads ravel and pull out quickly in use, while those sections of the edge where both the horizontal and perpendicular threads are long, or of about equal length, wear much better, thus producing an uneven degree of strength on the circumference.

It is evident that if all the sectors are cut from the material as above described—that is, having all the fibers in all the sectors running in the same direction—then the wheel will be of equal strength around the entire periphery, and I prefer the wheel made in this manner; but I do not limit myself to this construction, for when the material is of such character that sectors having the fibers disposed differently are equal in strength with such sectors as have all the fibers similarly disposed, sectors of both kinds may be used indifferently in building up the wheel, the object being to make the wheel of equal strength around its entire circumference.

Another advantage of cutting the material into the form of sectors instead of into the form of the complete wheel is economy, as no part of the material is wasted, as would be the case if the wheels were made out of material cut in round pieces, in which case both the central part and a large portion of the material between the round pieces to form the wheel would be cut to waste. Wheels made from sectors may be also made from cuttings.

I do not limit myself to any particular number of pieces to compose the wheel, nor to any particular shape of the different sectors, as these may be varied without departing from the invention. So, also, the pieces need not be cut parallel to the sides or ends of the material, but may be cut at any desired angle, so as to have the threads in the pieces of material running bias. There would be great uniformity of strength throughout the sectors if cut from bias material.

I am aware that it is not new to make a wheel of pieces of leather glued together in a groove around the central part. Such device is shown in Letters Patent No. 53,825. In such an arrangement, however, the pieces of which the wheel was composed were inclined toward the periphery of the wheel, and therefore presented substantially the side of the leather as the operating-surface. A wheel could not be made according to that disposition of its parts to present the end grain of the leather to the surface of the wheel unless the pieces be first reduced to wedge shape.

I am also aware that grindstones and wooden wheels have been made of sections of stone and of wood solid across the face of the wheel and disposed around a central part. I do not claim any such structures; nor do I claim broadly in this application a buffing or polishing device composed of a pile of pieces or scraps of yielding material united together and adapted to be carried by a central spindle.

What I do claim is—

A buffing or polishing wheel of textile fabric, composed of sectors, the fibers of all the sectors disposed substantially as described, whereby portions of the material which are of substantially equal strength are presented to the entire operating-surface of the wheel.

ALEXANDER LEVETT.
